CARD HOLDING ATTACHMENT FOR A TYPE-WRITER OR LIKE PRINTING MACHINE

Frederick C. Wendt, Farmington, Conn., assignor to Royal McBee Corporation, Port Chester, N.Y., a corporation of New York

Application February 26, 1957, Serial No. 642,455

6 Claims. (Cl. 197—135)

This invention relates to an attachment for a printing device and more particularly relates to a work card holding assembly which may be attached to the carriage of a typewriter or like machine. The work card holding assembly is adapted to receive and support relatively small sized cards, such as checks and the like, in a desired print receiving position during the typing operation.

Considerable difficulty is encountered when attempting to type a line of print on short stiff work cards. First, due to their rigidity, such cards resist conforming to the curved surface of the platen when being inserted into the machine in the normal manner. This necessitates a time consuming manipulation of the work cards and the paper feed control levers in order to initially bring the work card to the desired printing position. Secondly, because that portion of the work card which is to be printed on does not always lie flat against the operative surface of the platen impact of the type bars against said portion of the card is apt to cut or rupture the card material and/or smudge the printed figures.

One object of the instant invention is to provide a relatively simple and inexpensive work card supporting assembly which may be easily attached to and removed from a conventional typewriter carriage whereby the necessity of rolling the work card into the carriage in the usual manner is eliminated.

Another object of the invention is to provide a reliable means for supporting small work cards in a desired print receiving position whereby said cards may be quickly brought to and removed from said position without attaching said cards to any part of the typewriter platen.

A further object of the invention is to provide an efficient means for retaining the print receiving portion of the work card in contact with the operative surface of the platen.

Another object of the invention is to provide a simple means for supporting the work card so that no relative horizontal movement occurs between the work card and the platen during the typing operation.

Other objects will become apparent as the disclosure progresses.

For a more detailed description of the preferred embodiment of the invention reference is made to the drawings wherein:

Fig. 1 is a perspective view showing the card holding assembly and the principal parts of a conventional typewriter to which said assembly is to be attached.

Fig. 2 is a perspective view showing the card holding assembly in its secured position on the typewriter carriage.

Fig. 3 is a side elevation in partial section showing the card holding assembly operatively secured to the typewriter carriage.

Referring to Figs. 1 and 2, the card holding assembly comprises a U-shaped trough member 1 having a front wall 2 extending upwardly and terminating with an angularly disposed flange 3. The upper portion of the rear wall 4 of the said member 1 is rearwardly bent to

2

an inverted U-shaped profile and is vertically adjustably secured by any suitable means to an elongated cross bar 5. The card receiving slot formed by said U-shaped member 1 is closed at its left end by a bent over ear 6. Cross bar 5 may be appropriately offset or formed as at 7 in order to accommodate the contour of the particular machine with which the card holding assembly is to be used. At the left end of cross bar 5 there is secured a headed stud 8 and at the right end thereof there is secured a stud 9. A handle or finger piece 10 fastened to said bar 5 provides a convenient means for manually adjusting and positioning the card holding member 1.

The carriage supporting means for the card holding assembly comprises a locking member 11, which is secured by any suitable means to the left hand end of carriage frame 12 and which is provided with a wedge shaped notch 13. At the right hand end of the carriage 14 there is provided a latch assembly 18, Fig. 3, comprising a base plate 19 which is fastened by any suitable means to the right side of wall 20 of carriage 14 and which is provided with a laterally disposed ear 21 having a pin receiving hole 22. Pivottally mounted on the base plate stud 24 is a manually operable latch 25 having a forwardly extending hooked portion 26. Latch 25 is retained in its clockwise or release position against base plate stud 27 by means of a conventional type "over-center" spring 29 which is operatively secured between the latch stud 30 and the base plate stud 31.

30 A scale member 15 is secured to the carriage frame 12 by means of fastening screws 16. The mounted position of said scale member 15 is such that the upper edge 17 thereof is coextensive with the lower cam surface 43 of said notch 13. This arrangement facilitates the attachment of the card holding assembly to the typewriter carriage as will be hereinafter described.

In order to press the print receiving portion of the work card against the forward surface of the platen 32 there is provided a pair of spaced horizontally extending guides 33 and 34, Fig. 2, which are fixedly supported 40 on the machine base by any suitable means and which are positioned immediately adjacent the operative surface of the platen. The outer ends of said guides 33 and 34 are bent over to respectively form the angularly disposed guide surfaces 35 and 36 which engage and guide a work card which is being inserted into or withdrawn 45 from the machine.

The card holding assembly is attached to the typewriter carriage by first positioning the shaft portion of the headed stud 8 on the upper edge 17 of the scale member 15 as shown in Fig. 1. Cross bar 5 may then be moved to the left by means of handle 10 until the said shaft portion of stud 8 rides into the notch 13 of locking member 11 as shown in Fig. 2. The cross bar stud 9 is then aligned with and inserted into the hole 22 of base plate ear 21. Thereafter latch 25 is rotated counter clockwise from the release position shown by the solid lines of Fig. 3 so that the hooked portion 26 thereof engages the forward face of the cross bar 5 thereby securing the card holding assembly to the carriage 14. The "over-center" spring 29 assists in maintaining the latch 25 in the counter clockwise or locking position shown by the dotted lines of Fig. 3.

In the operation of the typewriter a work card 40 is inserted into the open end 41 of said trough member 1 and is moved to the left between said guides 33, 34 and the platen 32 until it engages the bent over ear 6 at the left end of trough member 1 as shown in Fig. 2. The work card 40 will then be horizontally and vertically positioned so that the subsequently typed figures will be located on the desired areas of card 40. The guides 33, 34 will insure that the print receiving portion of the work card is properly supported by platen 32 during the

typing operation. When the typing operation has been completed the work card 40 need only be moved to the right and withdrawn from the machine through the open end 41 of trough member 1. It will be seen that very little time and effort is required to insert, position and withdraw each successive work card.

It will be noted in Figs. 2 and 3 that the vertically disposed card receiving slot of trough member 1 is not coplanar with the vertical plane of the printing line 42 of the machine. By having the plane of said slot rearwardly offset from said printing plane, the work card 40, when in print receiving position will be flexed in the region immediately above the mouth of said slot. This flexure will increase the frictional contact between the card and the walls of said trough member 1 thereby resisting any tendency for the work card to move relative to the platen 32 as the latter is successively letter spaced to the left during the typing operation.

It is apparent that U-shaped trough members having slots of varying depths may be provided in order to accommodate either work cards of different sizes or work cards having differently located print receiving areas.

While there is in this application specifically described one form which the invention may assume in practice, it will be understood that this form of the same is shown for purposes of illustration only and that the invention may be modified and embodied in various other forms without departing from its spirit or the scope of the appended claims.

The invention claimed is:

1. In a printing device having a main frame, a carriage movably mounted on said frame, and a platen rotatably secured to said carriage; the improvement comprising, a work card receiving trough member, said member having a substantially vertically disposed card receiving slot which is open at one end, means on said member for limiting the extent of lateral movement of a work card which is laterally introduced into said member through said open end, latch means for detachably securing said member to said carriage, and work card guide means supported by said frame and adapted to press the print receiving portion of the work card against the operative surface of said platen.

2. In a printing machine having a main frame, a movable carriage mounted on said frame, and a work supporting platen rotatably secured to said carriage; the improvement comprising, an elongated trough member mounted on said carriage, said trough member having a work card receiving slot one end of which is open and the plane of which is horizontally offset from the printing line of the machine, and means supported by said frame for retaining the print receiving portion of the work card in contact with the operative surface of said platen.

3. In a printing device having a main frame, a carriage movably mounted on said frame, and a cylindrical platen rotatably secured to said carriage; the improvement comprising, an elongated trough member extending along the lower forward side of said platen, said member having a substantially vertically disposed work card receiving slot the plane of which is horizontally offset from the vertical plane of the print receiving portion of the work card,

means for detachably securing said member to said carriage, and work card guide means supported by said frame for retaining the print receiving portion of the work card against the operative surface of said platen.

4. In a typewriter having a carriage movably mounted on a main frame, and a cylindrical work supporting platen rotatably secured to said carriage; the improvement comprising, a U-shaped trough member, said member having a vertically disposed work card receiving slot therein the plane of which is rearwardly offset from the vertical plane of the printing line of the machine, spring biased latching means pivotably mounted on said carriage and adapted to engage and detachably secure said member to said carriage, stop means positioned adjacent one end of said slot to limit the operative position of the work card in one horizontal direction, and guide means supported by said frame and adapted to maintain the print receiving portion of said card in contact with the operative surface of said platen.

5. In a typewriter having a main frame, a carriage movably mounted on said frame, and a cylindrical platen rotatably supported by said carriage; the improvement comprising, a cross bar extending along the lower forward side of said platen, a trough member adjustably secured to said cross bar, said member having a substantially vertically disposed slot therein which is open at one end and closed at the other end, stud mounting means fixed at each end of said cross bar for engaging said carriage, spring biased latch means pivotally mounted on said carriage for detachably securing said cross bar and trough member to said carriage, and work card guide means supported on said frame for retaining the print receiving portion of the work card in contact with the operative surface of said platen.

6. In a typewriter having a main frame, a movable carriage mounted on said frame, and a cylindrical platen rotatably supported by said carriage; the improvement comprising, an elongated cross bar extending horizontally along the lower forward side of said platen, an aligning stud secured to each end of said cross bar, each of said studs being adapted to engage a slotted portion of said carriage, a spring biased latching means pivotally mounted at one end of said carriage and adapted to engage and detachably secure said cross bar to said carriage, a trough member adjustably secured to said cross bar, said member having a vertically disposed work card receiving slot therein the plane of which is rearwardly offset from the vertical plane of the typewriter printing line, means on said member for closing one end of said slot, and a pair of vertically disposed guides supported by said frame for retaining the print receiving portion of the work card in contact with the operative surface of said platen.
